RECORDING AND REPRODUCING SOUND

Hobart A. Simpson, Ocean Grove, and Thomas D. Burhans, Highlands, N. J., assignors, by direct and mesne assignments, to Jones Research Sound Products, Inc., a corporation of New York

Application June 23, 1931. Serial No. 546,196

5 Claims. (Cl. 179—100.3)

This invention relates particularly to sound recording and reproduction in connection with motion picture film.

Because of practical limitations in the width 5 of strip available for the sound record at the side of the picture frames, the quality of the recording has to some extent been handicapped in methods heretofore employed.

Special objects of this invention are to make 10 an accurate sound record, that is one of unlimited frequency response, without increasing the width of the sound track and further to actually reduce the width of the film track and hence gain added picture space on the film.

15 These objects are attained by the novel method of "angle recording" hereinafter fully described and broadly claimed.

The drawings accompanying and forming part 20 of the specification illustrate various embodiments and practical features of the invention but, as will be clear from the breadth of the claims, the structure may be modified in various ways without departure from the true spirit and broad scope of the invention.

25 Fig. 1 is a broken part sectional view illustrating sound recording apparatus embodying features of the invention; Fig. 2 is a broken detail view, looking in the direction of arrow 2 in Fig. 1 and showing in particular the inclined recording slit in relation to the film.

30 Figs. 3 and 4 are comparative views illustrating a narrow width film track produced by this invention and of a greater frequency range than the much wider track produced according to so-called "variable density" modern methods of recording; Figs. 5 and 6 are similar comparative views illustrating the narrow sound track of the present invention in relation to a "variable area" track of modern recording; Fig. 7 is a fragmentary 35 sectional view illustrating a modified form of glow tube, which may be used directly with the inclined slit without the interposition of a condensing lens; Fig. 8 is a broken sectional view illustrating an optical type of inclined slit; Figs. 40 9 and 10 are fragmentary views illustrating the third dimensional effects of this new recording on standard size and on the small 16 mm. size film; Fig. 11 is a diagrammatic illustration of the sound recordings on a greatly magnified 45 scale; Fig. 12 is a diagrammatic illustration of the special hook-up employed for recording; Fig. 13 is a somewhat diagrammatic illustration of the reproducing apparatus.

50 For recording, the apparatus illustrated generally in Fig. 1 may be employed, the same comprising a sound modulated glow tube or exciter

lamp 14, supported in line with the optical tube 15, carrying the lens system focused on the constantly travelling film 16. The optical system illustrated, consists of the lenses 17 for condensing the light from the glow tube through the slit 18, in the plate 19, onto the projecting lenses 20.

55 The optical tube is shown slidably mounted in the holder 21 for focusing purposes and as adjusted in such relation by the rack and pinion mechanism 22.

60 The light slit 18 differs from the conventional, in that it is inclined to the longitudinal axis of the film, instead of at right angles thereto. This will be clear particularly from Fig. 2.

65 For the purpose of fixing and predetermining 70 the incline or slant of the light slit, the barrel or tube of the optical system is rotatably journaled in the focusing sleeve 23 and is equipped with a worm gear segment 24, engaged by a hand operated worm 25 mounted on sleeve 23. The 75 worm gear segment is shown as cut in a ring 26, fixed to the lens barrel and forming an abutment at one end of the focusing sleeve and a similar ring 27 is shown fixed to the barrel at the opposite end of the sleeve, these two rings forming 80 shoulders engaging the ends of the sleeve to cause the lens tube to follow the longitudinal focusing 85 adjustments of the sleeve. The rotational adjustment of the tube within the focusing sleeve is effected through the worm gearing without interfering with or being affected by the focusing adjustment.

90 The glow tube holding sleeve 28 is shown as adjustable in the socket 29, toward and away from the end of the lens tube by the manually operable 90 rack and pinion 30. For locating the glow tube in the holder, the tube is shown gripped by the spring pads 31 of a surrounding sleeve 32, shiftably engaged at 33 by a screw 34, turning in the holder 28 and secured by a lock nut 35. By such construction, the tube is resiliently supported and may be readily centered with respect to the inclined light slit and this without interfering with the longitudinal adjustment of the tube holder with respect to the lens system.

95 A preferred form of recording circuit is illustrated in Fig. 12, where a microphone or pickup is indicated at 26, connected with an audio amplifier 37, feeding into a transformer 38, connected by leads 39, 40, directly with the electrodes of an exciter tube. A level indicator is shown connected across these leads at 41, for following the tube action and the energizing source for the tube is indicated at 42, connected with a variable 105 resistance 43 to the two leads of the tube.

In order that the results attained with this invention may be better appreciated, there is illustrated in Fig. 3, a section of film with a sound track 44 thereon as produced by the apparatus 5 described. This view shows how with the slit set at an angle to the longitudinal travel of the film there will be photographically produced on the film lines 45 of variable intensity in parallel relation, but inclined to the longitudinal extent of 10 the film, forming a sound track which is narrower than the customary variable density sound track 44a indicated in Fig. 4, but with the individual lines of recording actually as long or, if desired, the longer. This not only provides unlimited 15 frequency response, but allows greater transverse width 46 for the picture area on the film.

Actually, it is found that the inclined line recording gives a third dimensional effect, such as illustrated in Fig. 9, where it is shown that the 20 lenses may be of both variable density and of variable length.

The saving in transverse width of the sound track is so marked, that it has been found possible to run a sound track on the narrower width 25 film, commonly known as a 16 mm. film, as illustrated in Fig. 10, a result desired but heretofore impossible of attainment in the narrower forms of picture film.

The same advantages are attained, in this invention, for constant density variable area methods of recording, as will be seen in Fig. 5, where the recording lines are inclined to the longitudinal axis of the film to provide a film track 47 of the same or greater frequency characteristics, 30 but much narrower than the ordinary transverse line variable area sound track illustrated at 47a in Fig. 6.

To use the new angle recorded sound film, the reproducing apparatus is modified to the extent 35 that the light slit 18a is inclined to accord with the inclination of the record lines as illustrated in Fig. 13, which is a somewhat general showing of a sound head for a projector. This sound head may have a fixed angle slit or the angle may be 40 adjustable by means such as illustrated in connection with the sound camera shown in Fig. 1. If found desirable, to change the inclination for different types of recording, the angle may be marked on the film or the information be otherwise 45 applied, so that the operator of the projector may correspondingly set the inclination of the slit in the sound head, for instance, through the medium of suitable angle markings on the lens tube, or the like.

The structure employed may be modified in 50 various ways. For example, as indicated in Fig. 7, the condensing lens at the recorder may be omitted and the light be furnished direct to the slit by making the glow tube with a smaller end extension 14a and providing a light collecting reflector 48 for focusing the light from the smaller extension directly to the inclined slit. This permits of a more compact arrangement with the larger portion of the glow tube to one side of and substantially at right angles to the lens tube.

Also, the light slit may be of the optical, as distinguished from the mechanical type, such as indicated in Fig. 8, where the opposed inclined reflectors 49, 50, interposed between the condensing and projecting lenses transform the light from the glow tube into a line on the film, the inclination of which is governed by the rotational setting of the lens tube accomplished by the worm or screw adjustments 24, 25.

By the angle recording method of this inven-

tion, the new result illustrated in Fig. 11 is accomplished, that is, a record line is produced involving a constant length 51, determined by the length of the light slit, plus the variable more or less pointed tips 52 at the ends of the constant length section. These ends appear as fringes or peaks varying in shape from the sharply pointed areas to the more rounded areas shown and this extra recording gives an accuracy or fidelity of reproduction, which has not been accomplished heretofore, believed to be due to the greater frequency range, without cut-off. Thus a variable area recording effect is obtained without any mechanical shutter devices or other such elements as would introduce a lag or create a lack of synchronism.

The angle or inclination of the record lines may vary, but preferably it is between 75° to 89° to the horizontal or transverse dimension of the film. Within this range, the lines are actually longer than the horizontal recording on standard motion picture film and the overall width of the track is less than one-third the width of the usual sound track.

The gain in available picture area is thus considerable and the quality of sound reproduction is much improved. Also, it will be noted, the so-called "noise area" is cut down by two-thirds or more, in the example just given.

Another great practical advantage, is that the greater length of line in the angle recording of this invention permits of less amplification to gain the same signal strength, which in turn improves the quality of reproduction.

The invention also makes it possible to reprint from full width film onto 16 mm. or narrow film by photographic reproduction methods to produce for example, the sound picture film shown in Fig. 10.

It has been proposed heretofore, to produce 16 mm. sound film by printing according to photographic reduction methods from the 35 mm. commercial film onto 16 mm. film, but this has not been practical, because the reduction in scale of the sound track has required so much amplification to be used as to distort and substantially destroy the sound values. The present invention makes it possible to reprint from 35 mm. to 16 mm. sound film without impairing the sound record. For this special purpose, the angle recording on the 35 mm. film can be made equal in width to the present sound track now used with 110 35 mm. film, giving a length of line, which after reduction in printing onto the 16 mm. film will still be longer than the lines on the present 35 mm. film. Thus a record is produced on 16 mm. film equal to present recordings on 35 mm. film.

For general commercial purposes, the inclination of the light slits in the sound cameras and in the sound heads may be fixed at the same angle, so that film produced in any sound camera will be ready to run in any projector. If desired however, the projector may be so constructed as to permit of a range of angular adjustment and particularly for example, the range of adjustment necessary to shift from a standard horizontal line recording over to the new angle recording or vice versa. Thus, the entire optical system of the projector, including the mounting of the excitor lamp may be so constructed that it will carry the slit from the horizontal to the desired angular position or from the inclined slit position back to the horizontal position, stop shoulders for instance, being provided to limit the rotational throw of the optical system in

- either direction and a holding pin or pawl or the like, may be provided to releasably secure the optical tube in either one position or the other. It will be understood that the shifting of the light beam from the horizontal to the inclined or vice versa, may be accomplished purely by optical means, such as shown in Fig. 8, in which adjustment of the mirrors will accomplish what is effected by angular adjustment of the slit. 5
- 10 The variable area constant density recording illustrated in Fig. 5 may be produced by oscillographic methods with the reflecting prism arranged to transcribe the record lines inclined to the longitudinal axis or direction of travel of the film, instead of horizontally or transversely of the film as heretofore.
- 15 What is claimed is:
- 20 1. In a sound recording and reproducing, the combination of a sound camera for producing on motion picture film a sound record consisting of photographic parallel lines inclined to the longitudinal travel of the film and a sound reproducer having a photoelectric system inclined to the direction of film travel in correspondence with the 25 inclination of sound record lines produced by the sound camera, the inclination of the light record lines being between 75° and 89° to the transverse dimension of the film.

2. In motion picture sound recording and reproducing, the combination of sound recording and sound reproducing mechanisms having light slits inclined at the same angle to the direction of film travel and within the range 75° and 89° to the transverse dimension of the film. 80
3. A sound head for a motion picture projector, comprising an optical system including means for creating the effect of a light slit inclined to the direction of film travel through the head between 75° and 89° to the transverse dimension of the film. 85
4. As a new article of manufacture, a film having a constant width sound track thereon and composed of variable sound record lines in parallelism and inclined to the longitudinal extent of the film. 90
5. In motion picture sound recording and reproducing, the combination of sound recording and sound reproducing mechanisms having optical systems for creating the effect of light slits inclined at the same angle to the direction of film travel and within a range on the order of 75° to 89° to the transverse dimension of the film. 95
